UNITED STATES PATENT OFFICE.

DAVID YULEE READ, OF WASHINGTON, DISTRICT OF COLUMBIA, ASSIGNOR TO
ELLIOTT-FISHER COMPANY, A CORPORATION OF DELAWARE.

PAPER TABLE.

Application filed April 30, 1923. Serial No. 635,658.

To all whom it may concern:

Be it known that DAVID Y. READ, a citizen of the United States, residing at Washington, District of Columbia, has invented 5 certain new and useful Improvements in Paper Tables, of which the following is a specification, reference being had therein to the accompanying drawing.

This invention relates to flat platen type-writers, and more particularly to the equipment of a flat platen with an erasure table.

The object of the invention is to provide means facilitating erasures or other manipulation of the advanced ends of work 15 sheets or webs carried by the platen.

To the accomplishment of this object the illustrated embodiment of the invention includes a disappearing erasure table located at the front end of the platen, in an inoperative position, out of interference with the usual handling, feeding and cutting of the webs, but easily movable to its operative position to support the webs and facilitate erasures and the like.

25 In the accompanying drawings:—

Fig. 1 is a front end elevation of a flat platen equipped with my invention.

Fig. 2 is a plan view of the same.

Fig. 3 is a longitudinal section on the line 30 3—3 of Fig. 2, and

Fig. 4 is a perspective view of the table.

The platen 1 is mounted as usual in a platen frame 2 having a transverse front bar 3 the upper edge 4 of which is dropped 35 to a plane considerably below that of the platen to facilitate the feeding of paper webs under a cutter 5 located at the front end of the platen.

It will be understood that this forward 40 feeding of the webs to displace the printed portion thereof is effected by raising the cutter and drawing forward the front ends of the webs which are then severed by drawing them against the cutter. Obviously this operation 45 necessitates a clear unobstructed space in front of the platen and accounts for the dropping of the frame bar 4.

It sometimes happens, however, that the operator desires to make an erasure which if 50 done within the writing area of the platen results in smudging the paper or necessitates masking the intermediate carbon sheets. In order to leave the platen unobstructed and to at the same time provide a support over

which the paper webs may be drawn for erasures I provide a disappearing paper table 55. This table is preferably of sheet metal bent to form a platform 7 and a support 8 extending from the rear edge of the platform at an acute angle. At its lower edge the support 8 is hinged to the bar 3 as by trunnions 9 received by bearing brackets 10 secured to the bar.

The platform 7 is formed with extensions 11 which, in the operative position of the table overlie the elevated end portions of the bar 3, it being understood that the dropped edge 4 of the bar is only coextensive with the platen which is considerably narrower than the frame. Normally the paper table occupies the inoperative position shown in dotted lines in Fig. 2 with the support 8 lying against the front face of the bar 3 and the platform 7 extending under and behind the bar. When it is desired to make an erasure 70 the table is swung up to the full line position in Fig. 2. In this position the extensions 11 will rest on the bar 3 in rear of the center of gravity of the table. The operator may now draw the ends of the paper web over the table which will afford a temporary support 75 outside of or beyond the writing area and carbons and permit erasures to be made without smudging the paper or masking the carbons. When the erasure has been made 80 the table is merely tilted forward and caused to drop or disappear to its normal inoperative non-obstructing position.

After the erasure has been made the paper webs may be tightly grasped in rear of the 85 carbons and drawn back to their original positions by short backward movements which will not permit creeping of the webs upon one another.

What I claim is:

1. The combination with a flat platen, of a paper table normally occupying an inoperative position but movable into the plane of the platen to receive work sheets therefrom.

2. The combination with a flat platen, of a hinged paper table normally occupying a position out of the plane of the platen but movable into said plane adjacent to the front end of the platen.

3. The combination with a flat platen, of a paper table hinged in a plane below and in advance of the platen and movable into and out of the plane of the platen, said table in-

cluding a platform and a support disposed at an angle thereto, and means for sustaining the table when in operative position.

4. The combination with a platen, of a platen frame having a front bar in advance of the platen, a paper table including a platform and a support extending at an angle from the rear edge of the platform, and a

hinged connection between said support and the frame bar, said connection permitting the platform to swing into and out of the plane of the platen and to rest on the front bar in one position.

In testimony whereof I hereunto affix my signature.

DAVID YULEE READ.
